LUBRICATOR FOR AIR DRILLS

Filed Sept. 2, 1924

Inventor
Adolph Nelson.

By *A. J. O'Brien*

Attorney

UNITED STATES PATENT OFFICE.

ADOLPH NELSON, OF HUGO, COLORADO.

LUBRICATOR FOR AIR DRILLS.

Application filed September 2, 1924. Serial No. 735,365.

To all whom it may concern:

Be it known that I, ADOLPH NELSON, a citizen of the United States, residing at Hugo, county of Lincoln and State of Colorado, have invented certain new and useful Improvements in Lubricators for Air Drills; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to lubricating devices and has special reference to a device for lubricating the cylinders of air drills and analogous devices.

It is well known to those who have experience in the operation of air drills of various kinds and especially the ordinary rock drills, that they are often damaged from insufficient lubrication. An air-operated device presents difficulties in lubrication that are not present in steam-operated devices of a similar nature. Steam must naturally be at a temperature higher than the boiling point of water, as it cannot exist as steam at lower temperatures. The machine employing steam is therefore hot. Compressed air, unless heated previously to its introduction into the machine, enters the machine at the temperature of the surrounding air and consequently produces very low temperatures within the drill as it expands. This interferes to some extent with the lubrication.

It is my intention to provide a lubricating device which is adapted to force a lubricant into the stream of air passing to the drill. This lubricant will enter with the air and cause the valves and cylinder wall to be properly lubricated in spite of the low temperature therein.

My invention can be most clearly described and will be most readily understood when reference is had to the accompanying drawing, in which the invention is illustrated, and in which the single figure shows a vertical section of my lubricator, portions being shown in elevation to better disclose the actual construction.

Numeral 1 designates the body member of the lubricator which is an elongated tubular

member provided at each end with threads 55 2 and 3, which correspond, respectively, with the intake and the delivery ends of the device. Located a short distance from the intake end is a plug valve having a plug member 4, which is tapered and is rotatable 60 within a correspondingly tapered opening. On the lower side of the body member there is a projecting cylindrical wall 5 provided with an externally threaded portion 6 to which the cap 7 is operatively connected. 65 A washer 8 has a central spherical projection 9 and is pressed against the lower end of the plug 4 by means of a spring 10 which serves to hold the plug properly seated. The cap has a portion 11 of its outer surface hexagonal so that it can be conveniently rotated by means of a wrench. The upper end 12 of the plug is non-circular and adapted to be engaged by a handle 13 by means of which it may be rotated. By 70 rotating the plug 4 ninety degrees, the passageway 14 can be opened or closed at will. Just beyond the plug, the body member is provided with a cylindrical recess bounded by the internally threaded wall 15. An 75 opening 16 of less diameter than the recess connects the latter with the passageway 14. A perforated disk 17 rests on the shoulder formed by the flange 18.

Threadedly connected with the wall 15 is 80 a cylinder 19 whose inner surface is smooth and adapted to receive a piston 20, which is provided with an ordinary piston ring 21. A gasket 22 fits between the upper end of wall 15 and the lower surface of the 85 hexagonal portion 23 of the cylinder.

The outer surface of the cylinder above the hexagonal portion 23 is threaded for the reception of the elongated cap 24 whose upper end is closed by a wall 25 and has 90 a hexagonal portion 26 which may be engaged by a wrench. The piston has secured thereto a threaded stem 27 which cooperates with the threaded opening 28 in wall 25. The upper end of the stem 27 has a square 95 portion 29, by means of which it may be engaged by a wrench and rotated. With the parts assembled in the manner shown, it is obvious that the piston can be moved up and down within the cylinder by rotating the 100 stem 27.

Let us now assume a case in which the end having the threads 2 is connected to a source

of compressed air, while the other end is connected to an air drill or similar apparatus. By means of the plug 4, the passageway 14 is opened or closed, as above explained. With the valve closed, let us remove the cap 24 and the piston 20 from the cylinder 19 and fill the latter with a suitable hard oil or grease. The cap 24 is then replaced with the piston in its uppermost position. By turning the stem 27, the piston can be moved downwardly, by which action grease is forced through the openings in the disk 17 into the passageway 14 where it is caught up by the swiftly flowing air stream and carried to the machine to be lubricated. In the manner described and with the means disclosed, it is possible to lubricate the drill whenever desired with the minimum amount of labor and without 20 interrupting the operation.

From the above description it will be apparent that I have produced a simple device that can be applied to any existing air drill without the necessity of changing the latter 25 in the least.

Having now described my invention, what I claim as new is:

A lubricating device for mechanisms adapted to be operated by compressed air comprising, in combination, a tubular body member adapted to be connected in an air line connecting a source of compressed air to a machine, the body member being provided with a stopcock adjacent the end nearest the air supply, said body member having a circular recess in one side thereof and an opening of smaller diameter than the recess connecting the latter with the passageway in the body member, a perforated disk in the bottom of said recess, a cylinder threadedly connected to the wall of the recess, a cap threadedly connected to the outer surface of the cylinder, a piston within said cylinder, and a threaded stem connected to the piston, said stem being threadedly connected with the cap whereby the rotation of the stem will move the piston within the cylinder.

In testimony whereof I affix my signature.

ADOLFH NELSON.
